UNITED STATES PATENT OFFICE

RAYMOND A. ENGLISH, OF CLAY CITY, INDIANA

DUPLEX CAPSULE OR THE LIKE

Application filed July 8, 1929. Serial No. 376,628.

This invention relates to containers, and especially to containers for storing separately ingredients which are to be later mixed together, such as mercury and another metal or metals to produce an amalgam for dentists' use.

An object of the invention resides in the provision of a compartment receptacle or container in which the several ingredients may be separately stored and shipped, thereby providing for the exact measuring of the materials, preferably at the factory, thus avoiding waste of material such as occurs in the haphazard mixing of the materials as now practiced by dentists.

A further object of the invention consists in the provision of such a container in which the separately stored ingredients may be brought together for mixing by merely pressing the ends of the container toward each other, or by applying a turning movement to one end of the container with respect to the other end.

Other objects of the invention will be apparent from the following description when taken in connection with the accompanying drawing, in which

Figure 1 is a perspective view of one of the loaded containers or capsules.

Figure 2 is a longitudinal section through the capsule of Figure 1.

Figure 3 is a similar view of a slightly modified construction.

Figures 4 and 5 are perspective views of further modified forms of one of the capsule ends; and

Figure 6 is a longitudinal section through a still further modified construction.

The present container which I will now describe in detail is intended for use in connection with an amalgamator such as disclosed in my copending application, Serial No. 371,591, filed June 17, 1929.

The duplex capsule 1 as depicted in Figures 1 and 2 comprises two telescoping sections 2 and 3 of celophane or other material common in the construction of capsule containers and the like. In the present instance, however, a partition 4, also formed of gelatine, is provided to prevent communication between the

two ends of the container. This partition is formed with a skirt or flange 5 of sufficient diameter to engage over the open end of the section 3 of the capsule and is preferably provided with an outturned lip or flange 6 which abuts against the edge of the section 2 of the capsule.

The mercury 7 and granular metal 8, or whatever ingredients may be employed, are placed in the respective ends of the capsule, and the partition 4 is put in closing position on the section 3 prior to bringing the two capsule sections into final position as shown in Figures 1 and 2. The cap 4 may be held in position frictionally or cement may be employed if desired. The completed package is now ready for shipment or storage and when desired for use the operator merely presses the sections 2 and 3 toward each other so as to break the partition 4. By this means the previously separated ingredients are brought together and may be intimately mixed by placing the container and contents in the holding clips of the mixing machine as above referred to.

It will be readily apparent to those skilled in the art that a package as just described is of considerable value in dentistry as well as other arts in which the mixing of small amounts of materials is necessary. For instance, by the use of such a container the ingredients may be accurately measured out at the factory and placed in the containers, thereby not only insuring an absolutely correct proportioning of the ingredients but also avoiding a waste of materials such as is necessarily occasioned when the materials are hurriedly poured out from a storage supply during the process of filling a tooth, preparing an inlay, or the like. Furthermore, in practicing the old method of preparing amalgams, cements or the like, a considerable mess of the laboratory table, tools, etc., was involved which is entirely eliminated by using the duplex capsule. Moreover, the novel container disclosed herein provides for maintaining the materials in a most sanitary condition at all times by excluding air, fumes, moisture and the like, and yet permits of their instant mixing by merely pressing the

telescoping sections closer together as heretofore described.

In Figures 3, 4 and 5, I have shown modified forms of the invention in which the inner sections 9, 10 or 11 of the capsule is provided with one, two or more pointed projections or cutters 12. In the use of this form of the invention the respective sections are pressed together so as to cause the cutter 12 to penetrate the partition 4, and the sections may then be turned relatively so as to cause the partition to be cut loose from its flange 5 and thus permit the ingredients to be brought together. In other respects the disclosures of Figures 3, 4 and 5 are identical with the previously described construction.

In Figure 6 a somewhat different construction is disclosed which involves a separation of the capsule sections prior to the mixing of the ingredients. In this form of the invention the capsule 15 is of conventional type and may be employed for storing either of the ingredients used. The compartment for the second ingredient is provided by a third section or cap portion 16 which telescopes over the capsule 15 and is preferably frictionally held thereon.

Where this last described embodiment of the invention is used the materials may be brought together by first removing the cap 16, the sections of the capsule 15 are then separated and the contents of the cap 16 placed in the section containing the metal 8, after which the main capsule sections are brought together and the package is ready for the mixing machine.

From the foregoing description it will readily appear that by the present construction of duplex capsule and package I have provided for sanitary shipment and storage of exact proportions of ingredients to be later combined; that the ingredients thus prepared are ready for instant use by the operator without the necessity of weighing or gauging; that the ingredients are immediately brought together by a mere pressing together of the ends of the container and are then contained in the mixing receptacle ready for insertion in an amalgamator or other mixing receptacle; that the process of mixing may be carried out without in any way messing up the laboratory table, tools, etc.; and that the quantities of materials placed in the compartments of the containers may be graduated and the containers suitably marked so as to provide for large, small or intermediate mixtures of the final product.

In accordance with the patent statutes I have described what I now believe to be the preferred embodiments of the invention, but inasmuch as various minor changes may be made in the details of construction without in any way departing from the spirit of the invention I aim to include all such changes within the scope of the appended claims.

What I claim as new and desire to secure by Letters Patent is:

1. A duplex capsule comprising two telescopic sections and a partition, said parts being constructed and arranged to break said partition by a relative movement of the telescopic sections. 70

2. A duplex capsule including a body portion comprised of two telescopic sections and a partition so disposed as to be broken when the sections of the capsule are pressed toward each other. 75

3. A duplex capsule including a body portion comprised of two telescopic sections, a partition, a flange on said partition engaging over the open end of one of said sections, said elements being constructed and arranged so as to apply a disrupting force to the partition when the sections are pressed toward each other. 80

4. A duplex capsule including a body portion comprised of two telescopic sections, a partition disposed transversely of said capsule, and means on one of said sections to break said partition when the sections are pressed toward each other. 85

5. A duplex capsule including a body portion comprised of two telescopic sections, a partition disposed transversely of said capsule, and a cutter on one of said sections adapted to puncture the partition when the sections are pressed toward each other and to cut the partition as one of the sections is rotated with respect to the other. 90

6. A package comprising a compartment receptacle formed of telescopic sections, materials of different characteristics in said compartments, and means to cause communication between said compartments when the telescopic sections are pressed toward each other to cause a further telescoping movement. 100
